CLAIM

The ornamental design for a padded back panel, as shown and described.

DESCRIPTION

FIG. 1 is a top front right perspective view of a padded back panel showing the new design;

FIG. 2 is a bottom rear left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top view thereof; and,

FIG. 8 is a bottom view thereof.

The broken lines are for environmental purposes only and form no part of the claimed design.

The appearance of any portion of the padded back panel between the break lines forms no part of the claimed design. The padded back panel, is shown with symbolic breaks in its lengths. The appearance of any portion of the article beyond the break lines forms no part of the claimed design.

1 Claim, 8 Drawing Sheets
